UNITED STATES PATENT OFFICE

152,091

DESIGN FOR AN ELECTRIC COOKING APPLIANCE

Clarence Karstadt, Glen Ellyn, Ill.

Application February 14, 1947, Serial No. 136,915

Term of patent 7 years

(Cl. D81—10)

To all whom it may concern:

Be it known that I, Clarence Karstadt, a citizen of the United States, residing at Glen Ellyn, DuPage County, Illinois, have invented a new, original, and ornamental Design for an Electric Cooking Appliance, of which the following is a specification, reference being had to the accompanying drawings, forming part thereof.

Fig. 1 is a top plan view of an electric cooking appliance, embodying my new design;

Fig. 2 is a front elevational view thereof;

Fig. 3 is a rear elevational view thereof;

Fig. 4 is a view taken from the right side of Fig. 3; and

Fig. 5 is a view taken from the left side of Fig. 3.

I claim:

The ornamental design for an electric cooking appliance, as shown.

CLARENCE KARSTADT.
